UNITED STATES PATENT OFFICE.

KARL ALQUIST, OF SCHENECTADY, NEW YORK.

ELASTIC-FLUID TURBINE.

1,118,885.

Specification of Letters Patent. Patented Nov. 24, 1914.

Application filed April 16, 1914. Serial No. 832,228.

To all whom it may concern:

Be it known that I, KARL ALQUIST, a subject of the King of Sweden, residing at Schenectady, county of Schenectady, State 5 of New York, have invented certain new and useful Improvements in Elastic-Fluid Turbines, of which the following is a specification.

The present invention relates to reversible 10 elastic fluid turbines, more especially steam turbines, for marine propulsion built up of forward and reversing elements as is well known.

In connection with the design of steam 15 turbines, particularly multi-stage turbines of the impulse type, a comparatively large number of bucket rings are required in order to obtain a high efficiency. This makes the distance between bearing centers large 20 which necessitates a large shaft diameter. The large shaft diameter has further to be carried all through the length of the turbine in order to obviate the end thrust which would be caused by shaft packings of 25 different diameters, though otherwise, so far as stiffness is concerned, the shaft might be made to taper off toward the ends thereby saving in both material and weight. The large shaft diameter requires the use of 30 packings of greater diameter which means greater loss due to steam leakage. Further the packing clearances have generally to be increased as the surface speed of the shaft increases, so that the losses go up in a 35 higher ratio than the shaft diameter. In a reversing turbine the difficulties described are more pronounced because of the extra bucket rings which have to be added for reversing purposes and which further increase 40 the length of the shaft. A solution sometimes employed for overcoming the above difficulties which consists in running the turbines above the "critical" speed is not available for marine turbines, as a turbine 45 should "run through" the critical speed as quickly as possible, while a marine turbine will be called upon to run for long periods at any speed up to maximum speed.

The object of the present invention is to 50 overcome the above difficulties and to provide an arrangement which is compact, thereby providing for a shorter shaft length between bearing centers, and which further permits of the shaft being tapered from the 55 center toward the ends.

In carrying out my invention, I divide the forward elements into two groups, a high pressure group and a low pressure group, placed one on each side of the reversing elements which thus occupy the 60 middle portion in the turbine. I may use only two bearings for the unit, or I may provide also one intermediate bearing placed preferably between the reversing elements and the low pressure group of the forward 65 elements. The motive fluid for forward operation is led first to the high pressure group of forward elements and then by a suitable conduit across to the low pressure group. The flow through the forward low pressure 70 group is in a reverse direction to that through the reversing elements. This enables me to use a common exhaust chamber thereby saving materially in the length of the turbine and consequently in the shaft 75 diameter. By this arrangement I am also enabled to use a shaft having its largest diameter at the middle and stepped to a smaller diameter at the ends, and still balance the end thrust, as will be more fully 80 explained hereinafter.

Referring to the drawings wherein I have illustrated certain forms which my invention may take, Figure 1 is a side elevation partly in section of a turbine embodying the 85 features of my invention; Fig. 2 is an end view partly in section looking toward the right of Fig. 1, the part in section being taken on line 2-2 of Fig. 1; Fig. 3 is a view similar to Fig. 1 of a modified form, and Fig. 4 is a section taken on line 4-4, Fig. 3.

Referring first to Fig. 1, 5 is the turbine shaft carrying the two groups of forward elements 6 and 7, and the group of reversing elements 8, the latter being arranged between the groups of elements 6 and 7. As shown, the group 6 is the high pressure section and the group 7 is the low pressure section. 9 and 10 are suitable bearings for the shaft, and at 11 and 12 are shown the shell 100 shaft packings. 13 is the common exhaust chamber.

The motive fluid, as steam, is fed to the high pressure forward wheel or wheels by passages 14, and to the reversing wheel or 105 wheels by passages 15. These passages are preferably arranged in the same plane and are separated from each other by the wall or partition 16. Motive fluid is led to the turbine by the conduit 17 which is branched 110

as indicated at 18 and 19, the branch 18 leading to passages 14 and the branch 19 to passages 15. The passage of motive fluid through the conduit 17 is controlled by the 5 valve 20, which may be of any preferred form, hand controlled or otherwise, while the passage of fluid to the forward or reversing elements is controlled by the valve mechanism 21, which is arranged so that it 10 may be adjusted to direct the steam to either branch 18 or 19. In the case of forward operation the motive fluid first passes through the group 6, then by way of conduit 22 to group 7, and through group 7 to the chamber 15 13, and out through the exhaust opening. In reverse operation the motive fluid passes directly through the elements 8 to the exhaust chamber.

It will be noted that the shaft 5 is of 20 greatest diameter at the point midway between the bearing centers and that it is stepped down to a smaller diameter at the bearings. The shell packings 11 and 12 at the ends are thus small in diameter and the 25 end thrust is balanced as there is about the same steam pressure at the two ends. If found necessary the shaft diameters may be adjusted so as to obtain the desired pressure balance. It will also be apparent that 30 as the large packing diameters only occur at the low pressure stages, the leakage losses will be small.

The arrangement shown in Figs. 3 and 4 is substantially the same as that shown 35 in Figs. 1 and 2 except that in these figures an intermediate bearing is provided as shown at 24, and the turbine is shown as exhausting into a condenser 25 arranged below the same instead of through an opening at the top, as in Fig. 1. The same reference numerals have accordingly been applied to the corresponding parts in Figs. 3 and 4 as are used in connection with Figs. 1 and 2. When an intermediate bearing is 45 used, the rotors may conveniently be divided up into two groups of about equal size, one on each side of the intermediate bearing, and the exhaust passages 26 and 27 will then partly surround this bearing and connect the rotor housings so as to make them 50 form one rigid structure. In the arrangement as shown in Figs. 3 and 4, the shaft is reduced in size at the intermediate bearing, the shaft being greatest in diameter at 55 the points midway between the intermediate bearing and the end bearings.

In accordance with the provisions of the patent statutes, I have described the principle of operation of my invention together 60 with the apparatus which I now consider to represent the best embodiment thereof; but I desire to have it understood that the apparatus shown is only illustrative and that the invention can be carried out by other 65 means.

What I claim as new and desire to secure by Letters Patent of the United States, is:

1. A reversible elastic fluid turbine having its forward elements divided into two groups arranged one on each side of the 70 reversing elements.

2. A reversible elastic fluid turbine having its forward elements divided into a high pressure group and a low pressure group arranged one on each side of the 75 reversing section, the final stages of the low pressure group and of the reversing section being arranged to face each other and exhaust into a common chamber.

3. A reversible elastic fluid turbine having 80 its forward elements divided into a high pressure group and a low pressure group arranged one on each side of the reversing section, a conduit for conveying motive fluid to the forward and reversing 85 sections, and a common controlling valve mechanism for directing the motive fluid to either of said sections.

4. In an elastic fluid turbine, the combination of a shaft, bearings therefor, said 90 shaft having its greatest diameter midway between the bearings and stepped down to a smaller diameter at the bearings, forward elements carried by the shaft which are divided into two groups spaced apart, and a reversing section carried by the shaft which is located between the forward groups.

5. In an elastic fluid turbine, the combination of a shaft, a forward section carried 100 thereby which is divided into two groups spaced apart, a reversing section arranged between the two groups, and end bearings and an intermediate bearing for said shaft.

6. In an elastic fluid turbine, the combination of a shaft, a forward section carried thereby which is divided into two groups spaced apart, a reversing section arranged between the two groups, the final stages of the forward and reversing sections facing 110 each other and exhausting into a common chamber, and end bearings and an intermediate bearing for said shaft.

7. In an elastic fluid turbine, the combination of a shaft, forward elements divided 115 into a high pressure group and a low pressure group carried by the shaft and spaced apart, a reversing section between the two groups, the final stages of the low pressure group and the reversing section facing each other, end bearings for the shaft, and an intermediate bearing therefor located between the low pressure group and the reversing section.

8. In an elastic fluid turbine, the combination of a shaft, forward elements divided 125 into a high pressure group and a low pressure group carried by the shaft and spaced apart, a reversing section between the two groups, the final stages of the low pressure 130

group and the reversing section facing each other, end bearings for the shaft, an intermediate bearing therefor located between the low pressure group and the reversing section, a housing for the elements on the opposite sides of the intermediate bearing, and an exhaust chamber, the walls of which partly surround the intermediate bearing

and connect the housings so as to form one rigid structure. 10

In witness whereof, I have hereunto set my hand this 15th day of April 1914.

KARL ALQUIST.
